BOAT LAUNCHING CARRIAGE.

No. 390,543.

Patented Oct. 2, 1888.

UNITED STATES PATENT OFFICE.

HENRY J. WOODS, OF MUSKEGON, MICHIGAN.

BOAT-LAUNCHING CARRIAGE.

SPECIFICATION forming part of Letters Patent No. 390,543, dated October 2, 1888.

Application filed June 21, 1888. Serial No. 277,792. (No model.)

To all whom it may concern:

Be it known that I, HENRY J. WOODS, a citizen of the United States, residing at Muskegon, in the county of Muskegon and State of Michigan, have invented certain new and useful Improvements in Boat - Launching Carriages; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

5 This invention relates to improvements in carriages for life or other boats, by means of which they may be easily drawn from the water and readily launched therein.

10 The object of this invention is to provide a means whereby life-boats and other craft can be expeditiously transferred from their moorings down an incline into the water and returned to their original place with much greater ease than has been done by any other method; and the invention consists in constructing an iron carriage provided with a series of rollers onto which the boat is run, and also having another series of rollers which run on tracks laid on the inclined plane constituting 15 the floor from the boat-house to the water, together with a system of side rollers for keeping the boat in a perpendicular position when resting on the carriage; and the invention also consists in the arrangement and mechanism for holding the boat in place when in the boat-house and the means adapted for relieving the boat when it has reached the water, all of which will be fully described, and pointed out in the following specification and claims.

20 Figure 1 is a side elevation of the carriage, shown on the inclined plane. Fig. 2 is a plan view of the carriage complete. Figs. 3, and 4 are an enlarged elevation and plan of the catch for holding the boat on the carriage and also 25 for releasing the same. Fig. 5 is an enlarged side and front elevation of rollers on the sides of the carriage at the front end. Fig. 6 is an enlarged side and front elevation of center rollers on side of carriage. Figs. 7, 8, and 9 are an enlarged elevation and plan view of the devices arranged for holding a boat with a wooden keel upon the carriage, a cam being substituted for

the locking catch-bolt shown in Figs. 3 and 4. Fig. 10 is a transverse section of the carriage on line *x x* of Fig. 2, showing the manner in which the bottom of a boat is supported on said carriage.

25 A A represent two longitudinal bars of angle-iron placed parallel and a short distance from each other, the inside edges of which are the perpendicular sides of the same. These bars are placed sufficiently far apart to allow the keel of the boat to be guided between them without binding. These angle-iron bars carry 30 two series of rollers, B and C, which are pivoted to suitable braces fastened to the under side of the angle-iron. The series of rollers B are those on which the boat rests, and which project sufficiently far up in between the angle-irons to clear all the plates which connect 35 the frame together. The series of rollers C are those which carry the frame and run on a center track of iron, X, laid on the inclined floor of the ways. To the under side of the longitudinal angle-irons A A are secured the 40 plates D E and cross-bar F.

45 G represent two axle-bars, preferably made of square iron. To each side of these bars is fastened an angle-iron, H, the upper flanges of which are on a horizontal plane and flush 45 with the top of the axles, making a flat wide surface on the upper face. These axles are securely fastened by bolts or rivets to the under side of the plates D and at right angles to the bars A A. The outer ends of these axles 50 are provided with wheels I I, the bottoms of which are on the same plane as roller C and run on an iron track laid on the floor, but not shown in the drawings. The wheels I are provided with a lip or flange on the inside 55 edge of each. This lip runs in a groove formed in the floor, and is used for the purpose of keeping the carriage moving in a straight line when launching a boat or when returning it to its original place.

60 On the upper surface of the angle-iron H are securely fastened on each side two angle-iron bars, K K, the inside webs of which are perpendicular and placed the necessary distance apart to receive the side brackets and 65 rollers which keep the boat in a perpendicular position. These brackets and rollers are shown in enlarged views in Figs. 5 and 6.

70 The bar F is securely fastened to the under

side of the longitudinal bars A and K, and is for the purpose of giving stability to the center body of the carriage.

The brace-rods L, as shown in Fig. 2, are secured at one end to the plates E, which are fastened to the under side of the central bars, A, and at the other end either to the axle or to the bars H, which are fastened thereto. These brace-rods are for the purpose of rigidly keeping the front and rear ends of the longitudinal bars A A from deviating to either side.

Fig. 6 shows an enlarged view of side rollers used for the purpose of keeping the boat in a vertical position after it is returned to its place on the carriage.

m represents a casting provided with perpendicular slots, so as to enable the rollers N to be raised or lowered to suit the formation of different boats. The rollers N are journaled in a movable bracket, O, which oscillates on the pin a. The casting m is provided with a groove on each side, into which the pin a is placed. This casting, as shown in end elevation, Fig. 6, is provided with an inclined slot in the center, the object of which is to allow the roller to receive the greatest angle toward the center of the boat, so as to accommodate itself to the different forms of the hull while keeping the rollers from diverging from a horizontal line outward from the boat. This bracket m is secured between the angle-irons K in center of the carriage by bolts, as shown in Fig. 1.

Fig. 5 also shows an enlarged view of the side rollers, P, and casting or bracket Q, the position of which is shown in Fig. 2 at Q. This casting is securely bolted between the angle-irons K, the roller inclining somewhat toward the center of the carriage. The object of placing this roller opposite the front wheels is for the purpose of protecting the boat from injury in the event of its careening over when partially in the water and before it is fully released from the carriage. The roller being considerably higher than the wheels I, should the boat careen it would come in contact with the roller, and consequently would not be damaged thereby. The rollers N and P are preferably made of wood and covered with a casting of rubber.

R (see Figs. 1 and 2) represents the position of catch secured to the center bars, A A, and is used for holding the boat in place when moved and for releasing the same when in the act of launching. Enlarged views of this catch are shown in Figs. 3 and 4. R is the main casting, and is fastened to the angle-iron bars by bolts or rivets at b. This casting is formed with tapered sides for the purpose of guiding the keel to the center. One of these sides S is provided with a dovetailed groove, c, from top to bottom. This is for the purpose of inserting different thicknesses of metal, so as to fit the different thicknesses of keel. The opposite side of the casting is provided with a catch, T, which slides in a groove formed in the casting. The catch (see Fig. 4) is beveled

on one side and flat on the other, the object of which is to enable the boat as it is hauled into its place to automatically thrust back the 70 catch.

U is a lever pivoted at d to the main casting. The upper end of this lever is pivoted to the catch T, while the lower end is provided with a hole through which passes the spindle 75 V. One end of this spindle is bifurcated or provided with double jaws ee', and the opposite end with a nut or collar, e'', securely fastened thereto.

W is a spiral spring inserted between the 80 lever U and a projection of the solid casting R.

Y Y are two links, both pivoted at one end to the jaws ee'. The outer ends of these links are pivoted to the under side of the casting R. One of the links Y is provided with a slot at 85 m'', which is guided on a pin or bolt secured to the casting R.

Z is a hole in the casting, to which a rope or other device can be attached for the purpose of hauling the carriage from the water up 90 into its place, and n' is an eye provided on the outer end of one of the links Y, to which is attached a rope or other device for disengaging the catch when the boat is in the act of being launched.

In operating this device the carriage is run down the inclined floor and is partially submerged in the water. The boat is then run onto the carriage, the keel of which travels on the rotating roller B. On reaching the upper 100 end the keel forces back the catch T, compresses the spring W, and passes on, the side of the keel of the boat being provided with a hole suitable for the catch. When the boat reaches this position, the catch is immediately 105 released, and by the action of the spiral spring is forced into the opening, which holds the boat securely in its place. Suitable means are then employed by attaching a rope or other device to the casting R for hauling by said 110 rope the carriage, with its load, up the incline. Either a windlass, rope and tackle, or other device may be used, and manual or other power, to operate it.

In launching the boat a rope is attached 115 securely to a ring or cleat fastened to the floor, and is loosely coiled by its side. The other end of this rope is attached to a link Y at the eye n', and is of sufficient length that when the carriage has descended the incline and the 120 boat has reached its proper place the line or rope becomes taut and draws the links from the position shown in Fig. 4 to a straight line. This action compresses the spring W and releases the catch from the side of the boat, and 125 by the momentum the boat has already received in its progress down the incline it shoots clear of the carriage and into the water with considerable speed.

In the modification shown in Figs. 7, 8, and 130 9 of the drawings a cam, T', is substituted for the catch-bolt T, and is intended for use with boats having wooden keels, the bite of the cam upon the wood being sufficient to retain the

- boat in position upon the carriage, although it would be liable to slip upon the iron keels now in common use and with which the catch-bolt is preferred.
- 5 Having thus described my invention, I claim as new and desire to secure by Letters Patent the following:
1. As an improvement in boat-launching carriages, the combination of the central longitudinal ways provided with rollers to receive the boat's keel, the side wheels provided with supporting-wheels, and wheels or rollers bearing upon the sides of the boat to preserve its equilibrium, and an engaging and disengaging bolt to retain the boat in position upon the carriage when desired, all constructed and operating substantially as shown and described.
- 10 2. In a boat-launching carriage, the combination of the central longitudinal ways provided with rollers to receive the boat's keel, the side brackets provided with the supporting-wheels, and wheels or rollers bearing upon the sides of the boat to preserve its equilibrium, and the metallic plate R, jointed to the central longitudinal bars or ways, provided with inclined jaws S, and a spring-operated holding-bolt, T, arranged to retain the boat in position upon the carriage until it reaches the water, as set forth.
- 15 3. In a boat-launching carriage, the frame consisting of the central longitudinal ways provided with rollers for the reception of the keel of the boat, the side longitudinal bars provided with rollers to support the boat and supported by rollers, the transverse bars securing the longitudinal bars in position, the plate R, attached to the central longitudinal bars, its inclined jaws S, and the removable piece inserted into the dovetail groove c of the spring-operated locking-bolt T, all arranged as and for the purpose specified.
- 20 4. In a boat-launching carriage, the frame consisting of the central longitudinal bars carrying rollers for the boat's keel to run upon and rollers to support the frame, the side longitudinal bars supported upon rollers and carrying adjustable rollers for supporting the sides of the boat, the plates D, for securing the longitudinal and transverse bars together, and the plate E, holding the central longitudinal bars in position, in combination with the spring-operated bolt T and the links Y Y, arranged in the manner described for withdrawing the bolt, substantially as set forth. 45
5. In a carriage for boats, the combination of the central longitudinal bars forming ways for the keel, the side longitudinal bars carrying adjustable supports for holding the boat in an upright position, the transverse bars uniting the longitudinal bars, the plates D, for firmly uniting the transverse and longitudinal bars, the plates E, for holding the two central bars in their relative positions, and the braces L, all arranged substantially as set forth. 50
6. In a launching-carriage for boats, the combination of the longitudinal side bars with the adjustable brackets carrying oscillating rollers at their upper end for keeping the boat in an upright position, substantially as set forth. 55
7. In a launching-carriage for boats, the combination, with the frame, of the inclined oscillating rollers W, and the inclined rollers P, attached to the longitudinal side bars, K, to keep the boat on an even keel, substantially as 60 specified. 70
- In testimony whereof I affix my signature in presence of two witnesses.
